UNITED STATES PATENT OFFICE.

CHARLES W. CHISHOLM, OF WINNIPEG, CANADA.

DESIGN FOR A WASHER.

SPECIFICATION forming part of Design No. 21,194, dated December 1, 1891.

Application filed October 17, 1891. Serial No. 409,057. Term of patent 14 years.

To all whom it may concern:

Be it known that I, CHARLES W. CHISHOLM, of Winnipeg, in the Province of Manitoba and Dominion of Canada, have invented and produced a new and original Design for Washers, of which the following is a specification, reference being had to the accompanying drawings, forming part thereof, in which—

Figure 1 is a face view, and Fig. 2 an edge view, of a washer embodying my new design.

The design consists in the ornamentation and configuration shown.

The disk A is of circular shape, the peripheral edge of which is scalloped, as at α . In the center is a circular opening B, and between

the said opening and the scalloped edge a circular series of barb-like figures C appear, said figures extending into openings c and forming the inner walls or defining edges of said openings. Alternate teeth or scallops α at their under sides have beveled edges, as at α' , as seen in edge view, Fig. 2.

I claim—

The design for a washer herein shown and described.

CHARLES W. CHISHOLM.
